KNITTING DEVICE AND METHOD OF
KNITTING

Lillian M. Miller, Fort Harrison, Mont.

Application July 22, 1936, Serial No. 91,982

3 Claims. (Cl. 66—117)

This invention relates to improvements in knitting devices, the device consisting of a hollow shaft open at one end and having a hook resembling a crochet hook at the other end, and a pointed shaft resembling a knitting needle. The objects of the improvements are, first, to provide a hook on one of the needles to aid in manipulating the yarn or thread as the knitted material is worked from the plain needle on to the hooked shaft, and, second, to provide a means of easily and quickly transferring the knitted material from the hooked shaft back to the plain needle, after the knitted material has been completely worked from the plain needle to the hooked shaft.

It is also an object of my invention to provide a novel means of fitting the knitting needle within such a crocheting needle; to provide a hollow crocheting needle adapted to hold the knitting needle without frictional engagement therebetween; to provide a novel method of knitting hereinabove described; to provide a method by which knitting and crocheting may be combined; to provide devices which will facilitate knitting and will enable a beginner to learn it more quickly than ordinary knitting. I attain these and other objects of my invention by means illustrated in the accompanying drawings in which:

Figure 1 is a perspective view of the initial step in the operation of knitting, in which a person is casting on stitches on the needle to knit;

Fig. 2 is a perspective view of the operator in the act of knitting with my knitting device;

Fig. 3 is a perspective view of the knitted material after the loops have been worked from the left-hand needle to the right-hand needle;

Fig. 4 is a side elevation view of my devices;

Fig. 5 is a view partly in side elevation and partly longitudinal section of my hollow crocheting type needle;

Fig. 6 is a side elevation of my knitting type needle;

Fig. 7 is an elevational view (reduced size), of my two knitting needles with the material being knitted held entirely on one needle as is done at the outset of knitting each row;

Fig. 8 is a similar view with the material being gradually worked from the knitting type needle to the crocheting type needle;

Fig. 9 is a similar view of the needles after all the loops have been worked from the left-hand needle to the right-hand needle;

Fig. 10 is a similar view with the needles longitudinally aligned and ready for the knitting type of needle to be inserted in the crocheting type of needle;

Fig. 11 is a similar view after the knitting needle has been inserted into the crocheting type of needle;

Fig. 12 is a view similar to Fig. 10, after the knitted material has been transferred from the crocheting type of needle to the knitting type of needle; and

Fig. 13 is a similar view of the needles in position to proceed with the knitting.

Like numerals designate like drawings in each of the several views.

Referring to the accompanying drawings, I provide a knitting type of needle 1, having a flat, disk-like cap or head member 2 at one end and having the usual tapered point 3 at the other end. 15 I provide a hollow crocheting type of needle 4 having a chamber 5 extending nearly the entire length of the needle and stopping just short of the hook 6. The numeral 7 designates a strand of yarn in the process of being knitted and the numeral 8 designates loops formed on a needle in the process of knitting.

In knitting in the conventional way, the material being knitted is held first entirely on one needle. The material is gradually worked over to the other needle by forming new loops; this is done by slipping the pointed end of the needle held in the right hand through the first loop of yarn on the needle in the left hand, throwing the yarn over the point of the right hand needle, 30 twisting the needle to draw through the yarn, thus forming a new loop on the right hand needle. The loop from the left hand needle is dropped. After all the loops have been worked from the left hand needle to the right hand needle, the 35 needles are then changed to opposite hands and the same procedure is repeated. It should be noted that the yarn always feeds in at the points of the needles and runs from one side of the knitted material to the other as the knitting progresses. A most tiresome feature of knitting is due to the fact that the two needle points must be placed together and one hand used to throw the yarn over the two ends to make a loop, and the needle twisted so as to form a new loop. This continuous throwing over of the yarn is tiresome. In the so-called "German method" used in knitting, the end of the yarn is held to the left and the needle is twisted around deftly so as to pull the loop through with the end of the 45 needle, but this requires great dexterity and is more difficult to learn. My knitting devices eliminate the tiresome throwing over of the yarn and twisting of the right hand needle. They not only make knitting faster and easier but enable one to

combine crocheting and knitting and permit greater variety of designs than would be possible with either alone.

The feeding in of the yarn always takes place at the pointed ends of the knitting needles. In my method, by casting on the stitches on the plain needle first, these stitches can be worked over on the hook needle, using said hook to manipulate the yarn. When the material is all worked on to the hook needle, the operator can not simply change needles from hand to hand as in regular knitting. In this method the two needles are different, while in ordinary knitting the needles are exactly alike, therefore, after the material has been worked from the plain needle to the hook needle the knitted material must be placed back on the plain needle again. I have found that changing the knitted material from the hook needle back to the plain needle is preferable to interchanging the ends of the needles or other means which are features of devices of the prior art. This transfer of knitted material is quickly and easily accomplished by the knitting devices which I have designed and which are illustrated in the accompanying drawings, comprising a hollow shaft opening at one end and having a crochet type hook at the other end and a needle resembling an ordinary knitting needle and of such size that it may be fitted smoothly and snugly into the hollow part of the hollow shaft, but not retained by friction.

In my method of knitting with this apparatus, the material is held first on the plain needle 1 as shown in Fig. 7. Using the hook to manipulate the yarn, the material is worked on to the hooked needle 4 as in Fig. 8. Soon all the material is worked on to the hooked needle as in Fig. 9. Then the plain needle 1 is thrust into the chamber 5 of the hooked needle 4, as in Figs. 10 and 11. Then by grasping the hooked needle at the hook with one hand and the knitted material with the other hand, the knitted material is pulled off the open end of the hooked needle, the plain needle being pulled out of the hooked needle at the same time. The knitted material is thus transferred from the hooked needle to the plain needle as in Fig. 12. Then all is ready to repeat the knitting process, as in Fig. 13. This procedure is repeated over and over until the knitted article is completed. Changing the knitted material from the hooked needle to the plain needle can be accomplished quickly and easily.

While devices have heretofore been invented aimed at accomplishing the same results as my apparatus, they do it in a different way and lack the advantages of my device and have various disadvantages. For example, to place hooks on both needles would not allow a satisfactory operation. The hook is needed on the manipulating or active needle but a hook on the other needle interferes with the yarn slipping off the end. I have devised hooked caps or sleeves to be interchangeably fitted over the ends of knitting needles. These devices are, however, less desirable than the device disclosed in the accompanying drawings. As the pointed end of the needle must remain smooth and pointed so that it can still be used as a knitting needle when the sleeve is transferred to the other needle, no fastening device can be placed on it successfully. Therefore the sleeve of such a cap must be retained by friction. It must fit tight enough so that it will stay on during knitting but not so tight that it cannot be easily removed when necessary. This exactness is very hard to obtain in an article

which must be made cheaply. It is most difficult to manufacture cheaply a frictionally retained sleeve that will stay in place while knitting without wobbling, getting out of line, or slipping off. Furthermore, it is difficult to devise a frictionally retained sleeve that will give long service. Rubber linings are impractical. Also such attachments for knitting needles would have to be made for many different sizes of needles and needles are also made of different materials such as, steel, aluminum alloys, celluloid and wood. Also a difference in diameter of such a cap or sleeve and of the uncovered portion of the body of the knitting needle would interfere with its satisfactory use.

As illustrative of possible (but less desirable) means for carrying out my process of knitting, I could provide a needle having a stud on the end of which a knitting needle and a crochet needle cap or sleeve could be interchangeably mounted, or I could provide needles having a threaded stud on which a hook sleeve or cap having a correspondingly threaded socket could be interchangeably mounted.

My device as illustrated in the drawings has several substantial advantages over the modifications suggested. The hollow shaft of the crochet type of needle is of uniform diameter throughout and the knitting type of needle slides easily in and out of it without requiring a frictional engagement or the accurate machining of the parts which are necessary to secure frictional engagement between the needle and the hollow shaft, and which is an undesirable feature of devices of the prior art.

My knitting needle is easily placed in the hollow shaft 5, and is easily removed from the shaft, since it is not retained by friction, it does not have the undesirable features of a frictionally retained sleeve. It will give long service and will not wear out after a few hours knitting as would be likely to occur with a device having a resilient or flexible lining in the shaft to cause a frictional engagement with the needle as has been done in the prior art. The device is inexpensive to manufacture and can be sold at the same price as ordinary knitting needles.

By my method of knitting, new designs are possible and this fact alone would attract the attention of women who knit or crochet. The method of using my knitting devices is as easy to learn as the conventional method of knitting, and is faster and less tiresome to perform. Everything that can be done with ordinary knitting needles can be done with this device, as well as everything that can be done with crocheting needles; also crocheting and knitting can be combined easily and effectively in the same article.

What I claim is:

1. In a device of the type described, the combination of a knitting needle having a tapered end, a crochet type needle having a hollow shaft open at one end and of suitable size to hold the knitting needle without frictional contact between the surface of the needle and the inside surface of the hollow shaft, the knitting needle being easily removable, and being only of substantially the same length as the hollow shaft in which it is removably mounted.

2. Knitting devices, comprising a knitting needle, a hollow shaft of substantially the same length as the length of the knitting needle, said hollow shaft being open at one end and closed at the other end, the closed end having a crochet type hook, and a knitting needle of suitable size

to be snugly but removably fitted in the hollow shaft and without frictional engagement therewith.

3. A method for performing knitting consisting in using a knitting needle and a hollow crochet needle, transferring the knitted material from the knitting needle to the crochet needle, transferring the knitted material from the crochet needle by longitudinally aligning said needles and partially

telescoping them, and transferring the work from the crochet needle to the knitting needle, and repeating the transfer of the work from the knitting needle to the crochet needle loop by loop and repeating the operation, and continuing the above described process until the needle work is completed.

LILLIAN M. MILLER.
